FLUSHING SYSTEM

William S. White, Denver, Colo.

Application February 4, 1933, Serial No. 655,162

16 Claims. (Cl. 4—26)

This invention relates to a system for flushing toilets, urinals, slop sinks and other like fixtures, its primary object being to provide a highly efficient, though simple association of cooperative parts by which a fixture may be flushed with a comparatively small amount of water through the medium of an automatically stored supply of air-pressure.

Other objects of the invention reside in the provision of means to prevent water logging of the flushing system, to insure a substantially noiseless flush at the fixture, and to avoid the waste of water through leaks.

The invention is particularly adapted for use in homes and other places where direct pressure flush valves are not practical on account of an insufficient volume of liquid necessary to create siphonic action and where under ordinary conditions, a small pipe, while of ample size for domestic use, would not carry a sufficient volume of water to flush a closet bowl.

With the above and others in view, my invention consists, briefly, in drawing air into the system during each flushing-action, and to employ a portion of said air, in a compressed condition and so as to be available for use in expediting and accelerating the flow of water during the next following operation. The mere use of compressed air in flushing toilets is old in the art, but the method of providing a body of air under pressure automatically and without the necessity of replenishment by discontinuing the supply of water to the system, is novel in the art as it is at present known to me.

It is obvious that the arrangement of the elements essential in attaining the objects of my invention, must be variable in order to adapt the system for use under different conditions, particularly with reference to the location of the toilet, the source of water-supply and the construction of the building in which the system is installed, and in order to convey an understanding of possible modifications required under such varying conditions, several examples have been illustrated in the accompanying drawings.

Figure 1 represents a sectional elevation of the system in what may be considered as being perhaps its simplest and, therefore, preferable form, and

Figures 2 to 6, inclusive, are similar views of modifications of the arrangement and construction shown in Figure 1.

In Figure 3, the source of water and air-supply are associated with a bath-fixture, and in Fig-

ures 4, 5 and 6, the toilet-fixture has been omitted as being in the same relative position to the other elements of the system as in Figures 1, 2, and 3.

Figure 7 is a sectional fragmentary view showing a modification by which two chambers included in the invention communicate separately with the flush-valve.

Like reference characters designate corresponding parts throughout the views.

Referring first to Figure 1 of the drawings, the toilet shown at 5, is, as usual, equipped with the conventional flush valve 6, commonly known as the flushometer.

The source of water supply is shown in the form of a supply pipe 7 terminating in a jet 8. The jet extends into a pipe 9 of the system beyond an air-intake opening 10 in the pipe, controlled by a check-valve 12.

A tank 13, in this instance located below the floor 14 upon which the toilet is installed, is divided into two compartments A and B by a partition 15. The two compartments constitute two separate and distinct chambers which may be formed in one and the same tank as in the present illustration, or which may be separated from each other to be located at different points of the installation, as in modifications hereinafter to be described.

The chamber A is in the operation constantly filled with water and thus provides a reservoir for the supply of a body of water immediately available to flush the toilet when the flush valve thereof is opened, while the chamber B functions to receive a surplus of water admitted to the reservoir when the flush-valve is closed, and by the advance of said surplus, produce a body of air under pressure, which provides a force to eject the contents of the reservoir when the flush-valve is reopened.

The pipe 9 connects with an opening in the reservoir water-chamber A and a pipe 16, in which the flush valve is connected, connects with an opening of the same chamber preferably opposite to the other. An opening 17 in the partition connects the two chambers.

In the operation of the system illustrated in Figure 1, pipes 9 and 16, the chamber A and part of the chamber B are normally filled with water, while a body of air entrapped in the upper portion of the chamber is held in a state of compression by the water pressure. When the flush valve is opened, the air expanding in the upper portion of the chamber B, forcibly drives the water through the opening 17 of the partition

and with the water contained in the chamber A and the pipe 16, into and through the toilet.

The flushing action is, of course, aided by the water ejected through the jet 8 of the water-supply pipe, into the pipe 9, and owing to the partial vacuum created in the pipe, new air is drawn into the pipe through the valve-controlled intake-opening 10. This air after entering the chamber A, works up through the opening of 10 the partition into the chamber B after the flushing operation and replaces the water which was expelled from the chamber, and when subsequently the flush valve is closed, this air entrapped in the upper portion of the chamber will be compressed by the pressure of the water which will be supplied from the source until the system is restored to its original condition. It will thus be seen that a body of compressed air is constantly formed and maintained in the chamber B in a 15 completely automatic action, and that, owing to the presence of said air body, the toilet is flushed with a minimum amount of water, and with the minimum of noise.

An advantageous result obtained in the operation is that when the toilet is being flushed and the pressure in the chamber A is consequently relieved, pressure may be constantly maintained in the chamber B.

By reducing the pressure in chamber A when the flush valve is opened, air is taken into the chamber regardless of the pressure in the chamber B and said air will be transferred to the last-mentioned chamber when the flush-valve closes, even though pressure is maintained in said chamber.

It follows that even though the compression chamber B provides a repellent force, air is forced into the chamber when the pressure in the chamber A exceeds said force, and will be taken into the water-chamber or reservoir A regardless of said force in chamber B while the operation is taking place.

In Figure 2 of the drawings, the jet 8 of the water-supply extends into the outlet pipe 16 of chamber A instead of extending into the inlet pipe of the same as in the arrangement shown in Figure 1. The outlet pipe is of larger diameter than the inlet pipe 7 and the valve-controlled air-intake is in the chamber A, as at 18, instead of in the inlet pipe as before. The chambers are again provided by two compartments of a divided tank 13, which, in this instance, is located above the toilet instead of below the same, as in Figure 1. The compartments communicate through an opening 17 in the partition 15, but in addition to said opening, a pipe 19 is provided which, at its upper and lower ends, opens into the compartment B and the compartment A, respectively, and which adjacent its upper end has another opening 20 communicating with the compartment B.

Again, under normal conditions, the chamber A and part of the chamber B are filled with water, and air is compressed in the upper portion 65 of the chamber by the water-pressure. When the flush valve is opened, the compressed air forces the water in the chamber B out through the pipe 19 by way of its open upper end and the auxiliary opening 20 and through the pipe 70 16 to the toilet.

This swiftly moving body of water assisted by the water issuing from the jet 8 draws the water from the chamber A and creates a partial vacuum, causing atmospheric air to be drawn in through 75 the valve-controlled intake 18. When the water

has been forced out of the chamber B to a level that it no longer covers the upper end of the pipe 19, the excess air in the chamber will enter the pipe and mingle with water flowing through the opening 20, thus adding impetus to the body flowing through the pipe 16 and exerting a greater pull on the water discharging from the chamber A, to draw air into the same.

During this operation, the excess air expelled from the chamber B leaves a space to be filled by air drawn into the chamber A through the intake, which is not needed in the flushing action and after the flush-valve is again closed, the air will enter the chamber B through the opening 17 and will accumulate in the upper portion of the chamber, to be compressed by the water pressure after the chamber A and part of the chamber B are re-filled with water.

It will be apparent that the flushing action may be regulated not only by means of the flushing valve, but also by varying the size of the chamber B and the height of the pipe 19 within the same.

The opening through which the air taken into chamber A passes into chamber B is not necessarily located in the partition. It may, if so desired, be formed in the pipe 19 or conducted from one chamber to the other by means of a by-pass or other convenient and suitable means. Since variations of this character are obvious, they have not been shown in the drawings.

Here also a repellent force in chamber B will not prevent air from entering the reservoir A and the subsequent recharging of chamber B without the need of discharging the contents of the same, beyond what is required to flush the fixture and preventing waste.

In Figure 3 is shown a practical method of employing a bathtub or basin for the supply of water and the intake of air. The chambers A and B are in this installation, provided by two separate tanks 21 and 22, which, as in Figure 1, are located below the toilet. However, the chambers are not one above the other as in the installations of Figures 1 and 2, but they are placed next to each other at substantially the same level.

The water jet 8 is, in this construction, connected with the cold water supply pipe of the bath or basin, as at 23, and a pipe 24 has an open end into which the jet extends. Adjacent said open end of the pipe 24, is a branch pipe 25 in which the check-valve 12 is connected and which connects the pipe 24 with the waste pipe 26 of the bath.

An opening in the bottom of chamber B connects with a U-shaped pipe 27, the open end of 55 which is in the upper portion of the chamber A, and a pipe 28 having an open end in the bottom portion of the chamber A, connects with the flush valve 6 of the toilet.

When the flush valve is opened, the compressed air in the upper portion of chamber B forces the water from said chamber through the pipe 27 into the upper portion of the chamber A and thence the water together with that of the chamber B passes through the pipe 28 and past the open flush valve 6 to the toilet. In the meantime, the influx of water from the jet 8 draws air through the branch pipe 25 into the pipe 24 and into the chamber A, from where it escapes with the water through the pipe 27, into the chamber B, where it accumulates to be subsequently compressed by the water pressure when the flush valve is closed. The pipe 28 may have an aperture 29 to allow the gradual escape of excess air, and here again the 75

intake of air is not prevented by the pressure in chamber B.

It is to be understood that the connection 27 between the chambers should be restricted and 5 much smaller than the pipe 28 to relieve back pressure.

In Figure 4, the pipe 16, in which the flush valve is connected, is in direct communication with the pressure chamber B by means of the upright 19 which, in common with the same pipe of the construction shown in Figure 2, is open at its upper 10 end and has auxiliary openings 20 and 20a. The jet 7 of the water-supply extends into the pipe 9 leading to the water chamber A, as in Figure 1, 15 and the air is drawn into the system through the valve-controlled intake 10 in the pipe 9. The chambers are, as before, formed in a tank 13 by means of the partition 15 having an opening 17 and the tank is on about the same level as the 20 toilet.

In operation, the air pressure in the chamber B, forces the water from the chamber through the toilet when the flush-valve is opened.

The air is drawn into chamber A by the influx 25 of the water discharged by the jet 7 and the air entering the chamber B through the opening 17 in the partition is, as before, compressed in the chamber B by the water pressure when the flush valve is closed.

After the water level in chamber B falls below 30 the end of the pipe 19, the excess air is discharged through said end, while the water passes through the auxiliary opening 20.

In the modification illustrated in Figure 5, the 35 chambers A and B are provided, as in Figure 3, by the separate tanks 21 and 22, one of which may be located above the floor of the toilet while the other is placed below the same.

The pipe 16 of the flush valve connects with 40 the lower portion of the pressure chamber B and is controlled by a check-valve 30, a branch 31 of the pipe 16, above the check valve connects with the bottom of the chamber A and into this branch 45 extends the jet 8 of the water-supply. The upper portion of chamber A connects with the bottom portion of chamber B by a pipe 32 and the valve-controlled air-intake is located, as in Figure 2, in the lower portion of chamber A. When the flush valve opens, the body of compressed air in 50 chamber B forces the water in chamber B past the check-valve 30 into the toilet, while at the same time the jet 8 forces the water in A to pass to the toilet through the branch pipe 31. The check-valve prevents the return of water to the chamber 55 B, and the excess of pressure causes the water in chamber A to be driven through the pipe 32 into the chamber B.

The influx of water by means of the jet connected with the source of water supply, draws 60 air into the chamber A through the valve-controlled intake 18, and this air moving upwardly in the chamber, passes through the pipe 32 into the chamber B after the valve is closed, where, after the flush valve is closed, it is compressed by 65 the water-pressure as before.

In Figure 6, the two chambers, A and B, are located in substantially the same position as in 70 Figure 5.

The flush-valve pipe 16 connects with an opening 75 in the lower portion of the water-chamber A, and the jet 8 of the water-supply projects into this opening, as in Figure 2.

The valve-controlled air-intake is in the chamber A, as in Figure 5. A pipe 33 connects the 75 lower portion of the pressure chamber B with the

upper portion of the chamber A, similar to the arrangement shown in Figure 5.

Again the operation is on the same principle upon which the entire invention is based.

When the flush valve opens the water shooting 5 into the pipe 16 from the jet 8 of the water supply passes to the toilet, together with the water driven from the two chambers by expansion of the body of compressed air in the chamber B, it being understood that the water of chamber B is driven 10 upwardly into the chamber A through the pipe 33. Air is drawn into the chamber A through the intake and after the flush-valve is again closed, this air escapes through the pipe into the chamber B, where it is compressed by the water pressure, ready for use in the next following operation.

In the modification shown in Figure 7, both 15 the chamber A and the chamber B are connected with the flush-valve. For this purpose, two pipes, 20 34 and 35, of smaller diameter are provided, one connecting with the chamber A and one with the chamber B, while both are connected with the flush-valve as by means of a T-fitting 36. In this manner, water may be expelled directly from the 25 chamber B, as well as from the chamber A, and by placing a valve 37 in the pipe leading from the pressure chamber B, the supply of water to the fixture and the pressure in the chamber B may be regulated. In fact, it is possible to automatically 30 regulate the supply and the pressure by the use of a pressure-sensitive valve in the place of a hand-adjusted valve.

Many other variations in the construction and 35 arrangements of the elements comprised in the invention, may be made within the scope and spirit of the same, as defined in the hereunto appended claims, those hereinbefore described having been found to be most practical and efficient under varying conditions.

What I claim and desire to secure by Letters 40 Patent is:

1. A system for flushing a toilet or the like, provided with a flush-valve, comprising in combination with a source of water-supply, a reservoir and an air-compression chamber communicating for the passage of water from one to the other, a pipe connecting the reservoir with the flush-valve, a pipe connected with the same reservoir and having a valve-controlled air-intake, and 45 a jet connected with the source and extending into the last-mentioned pipe.

2. A system for flushing a toilet or the like, provided with a flush-valve, comprising in combination with a source of water-supply, a reservoir and an air-compression chamber communicating by means of a perforated partition, for the passage of water from one to the other, a pipe connecting the reservoir with the flush-valve, a pipe connected with the same reservoir and having a 50 valve-controlled air-intake, and a jet connected with the source and extending into the last-mentioned pipe.

3. A system for flushing a toilet or the like, provided with a flush-valve, comprising in combination with a source of water-supply, a reservoir and an air-compression chamber communicating for the passage of water from one to the other, a pipe connecting the reservoir with the flush-valve, an air-intake communicating with the same 55 reservoir, and a jet connected with the source, and positioned relative to the air-intake, to draw air by suction into the reservoir.

4. A system for flushing a toilet or the like provided with a flush-valve, comprising in combination with a flush-valve, 60

- tion with a source of water-supply, a reservoir and an air-compression chamber communicating by means of a perforated partition, for the passage of water from one to the other, a pipe connecting the chambers and having openings at different elevations in the air-compression chamber, a pipe connecting the reservoir with the flush-valve, an air-intake communicating with the same reservoir, and a jet connected with the 5 source, and positioned relative to the air-intake, to draw air by suction into the reservoir.

5. A system for flushing a toilet or the like, provided with a flush-valve, comprising in combination with a source of water supply, a reservoir and an air-compression chamber communicating for the passage of air and water from one to another, an air-intake communicating with the reservoir, a jet connected with the source of water-supply and positioned relative to the air-intake to draw air into the reservoir by suction, and a pipe connecting the air-compression chamber with the flush-valve.

6. A system for flushing a toilet or the like, provided with a flush-valve, comprising in combination with a source of water-supply, a reservoir and an air-compression chamber communicating for the passage of air and water from one to another, an air-intake communicating with the reservoir, a jet connected with the source of water-supply and positioned relative to the air-intake to draw air into the reservoir by suction, and a pipe connected with the flush-valve and having openings at different elevations in the air-compression chamber.

35. 7. A system for flushing a toilet or the like, provided with a flush-valve, comprising in combination with a source of water-supply, a reservoir and an air-compression chamber communicating for the passage of air and water from one to another, an air-intake communicating with the reservoir, and a pipe connecting the reservoir with the flush-valve, and a jet connected with the source of water-supply and disposed adjacent the connection of the last-mentioned pipe with the reservoir whereby to draw air into the reservoir by suction.

8. A system for flushing a toilet or the like, controlled by a flush valve, comprising in combination with a source of water-supply, a reservoir and a compression chamber connected for the passage of air and water from the reservoir to the compression chamber, a connection for the passage of water from the reservoir and the compression chamber to the toilet when the flush-valve is opened, an air-intake communicating with the reservoir, a jet connected with the source of water-supply and positioned relative to the air-intake to draw air into the reservoir by suction when the flush-valve is opened, the connections of the reservoir and the compression chamber with each other and with the toilet being such as to maintain air-pressure in the compression chamber during the flushing-action and to transfer air from the reservoir to the compression chamber, when the flush valve is closed.

9. A system for flushing a toilet or the like, controlled by a flush valve, comprising in combination with a source of water-supply, a reservoir and a compression chamber both connected with the flush valve, and communicating with each other for the passage of air and water from the reservoir to the compression chamber, an air-intake connected with the reservoir, and a jet connected with the reservoir, and positioned relative

to the air-intake to draw air into the reservoir by suction.

10. A system for flushing a toilet or the like, controlled by a flush valve, comprising in combination with a source of water-supply, a reservoir and a compression chamber both connected with the flush valve, and communicating with each other for the passage of air and water from the reservoir to the compression chamber, a valve controlling said connections, an air-intake connected with the reservoir, and a jet connected with the reservoir and positioned relative to the air-intake to draw air into the reservoir by suction.

11. A system for flushing a toilet or the like, controlled by a flush valve, comprising in combination with a source of water supply, a reservoir and a compression chamber, both connected with the flush-valve, and communicating with each other for the passage of air and water from one to the other, an air-intake connected with the reservoir, and a jet connected with the reservoir, and positioned relative to the air-intake to draw air into the reservoir by suction.

12. A system for flushing a toilet or the like, comprising in combination with a source of water supply, a system of interconnected conductive elements, connected at one end with the source to receive water therefrom and having at its opposite end an outlet for the discharge of the water, and a flush valve controlling the outlet, the said elements including a water reservoir and a compression chamber having a water space in connection with the reservoir, and having a normally closed space for the compression of air by the influx of water from the reservoir when the flush valve is closed, said body of air acting upon the bodies of water in both the compression chamber and the reservoir for their forcible movement to the outlet when the flush valve is opened and a normally closed air intake opened by the flow of water through the system, to augment the body of compressed air in the compression chamber and to replenish said body after the flush valve is re-closed.

13. A system for flushing a toilet or the like, provided with a flush valve, comprising in combination with a source of water supply, two chambers communicating for a restricted passage of water from one to another, a conductive connection for the passage of water from the chambers to the toilet, controlled by the flush valve, a connection between the source of water supply and one of the chambers, and a valve controlled intake for drawing air into the system by the flow of water from the source to the chamber with which it is connected, the other chamber having a space for the compression of water entering the chamber when the flush valve is closed.

14. A system for flushing a toilet or the like, having a flush valve, comprising in combination with a source of water supply, a body of water held under pressure by water in the system when the valve is closed, a second body of water having a restricted communication with the first mentioned body and connected with the source of water supply, and a valve controlled air intake for drawing air into the second body by the flow of water from the source, the system being connected with the toilet for the supply of water thereto when the flush valve is opened.

15. A system for flushing a toilet or the like controlled by a flush valve, comprising in combination with a source of water supply, a reservoir and a compression chamber both connected

with the flush valve and communicating for the passage of air and water from the reservoir to the compression chamber, and a valve controlling the connection between the compression chamber and the flush valve.

16. A system for flushing a toilet or the like controlled by a flush valve, comprising in combination with a source of water supply, a reservoir and

a compression chamber both connected with the flush valve and communicating for the passage of air and water from the reservoir to the compression tank, and a pressure sensitive valve controlling the connection between the compression chamber and the flush valve. 5

WILLIAM S. WHITE.
